UNITED STATES PATENT OFFICE.

DAVID CRAIG, OF MELROSE, MASSACHUSETTS, ASSIGNOR OF ONE-HALF TO CHARLES H. LOVESY, OF BETHLEHEM, PENNSYLVANIA.

BUILDING.

1,083,876.

Specification of Letters Patent.

Patented Jan. 6, 1914.

Application filed April 16, 1909. Serial No. 490,383.

To all whom it may concern:

Be it known that I, DAVID CRAIG, a citizen of the United States, and resident of Melrose, in the county of Middlesex and 5 State of Massachusetts, have invented new and useful Improvements in Buildings, of which the following is a specification.

This invention relates to a building, and particularly to a knockdown and portable 10 building of concrete or the like, and consists essentially of a frame made up of a plurality of upright members and cross members separably connected together, and a plurality of slabs of concrete, or similar 15 hardened plastic material, which may be reinforced or not as desired, separably attached to said frame, so that the structure may be readily and quickly assembled or taken down for the purpose of storage or 20 transportation without injury to the parts. This improved knockdown building may be packed into very small compass, and when set up produces a strong, durable and fire-proof structure.

25 Other features will hereinafter be described and pointed out in the claim.

While my invention is applicable to buildings generally, and may be put to a great 30 variety of uses, it may be well illustrated in a portable automobile house or garage in which fire-proof construction is of the greatest importance. I will therefore address my description to a building suitable 35 to be used as a portable garage by way of illustration, but desire to have it understood that the invention is not limited to such use.

In the accompanying drawings which 40 illustrate certain embodiments of my invention,—Figure 1 is a front elevation of a house embodying my invention, partly in section; Fig. 2 is a side elevation of said house, partly in section; Fig. 3 is a horizontal section of the walls of said house taken through the joint between two tiers of the 45 slabs; Fig. 4 is an enlarged detail, in horizontal section, showing one method of separably fastening the slabs to the uprights at the sides and corners; Fig. 5 is an enlarged detail, in horizontal section, showing another method of separably fastening the 50 slabs to the uprights; Fig. 6 is an enlarged detail, partly in plan and partly in section, showing still another method of separably fastening the slabs to the uprights; Fig. 7 55 is a plan view, partly in section, of one of

the slabs showing a method of reinforcing the same; and Fig. 8 is a side elevation, partly in section, of the slab shown in Fig. 7.

The frame of the house is made up of the upright members A, which are preferably 60 beams of concrete reinforced by rods *a* embedded therein. The upright members A are preferably made square and of the same breadth as the air space between the inner and outer walls when a double wall is used. 65 Those uprights at the side of the building, or in any wall longer than a single slab, are provided with lateral projections *a'* through which the bolts pass fastening the slabs to the uprights. The cross members 70 of the frame, supported by the uprights, comprise the side sills B, which may be made with an inclined or beveled top surface to engage the sloping roof; the end sills C; and the ridge pole D. Each of 75 said frame members is preferably made of concrete or the like reinforced by metal rods *a* similarly to the upright members. The side sills B are provided at intervals with the lugs *b* for bolts to fasten the roof slabs 80 to the side sills; and the ridge pole D is provided on top at each side with a bead *d* overhanging and covering the joint between the ridge pole and the ends of the roof slabs.

The frame members may be separably 85 held together by suitable removable fastening means, such as the screw bolts *b'* passing through holes in the side sills B and into sockets in the ends of the uprights A, and the angle brackets *c* removably screwed to 90 the end sills C and the uprights A.

The walls of the building consist of a 95 plurality of covering slabs E of concrete or the like. These slabs are preferably reinforced in some manner as by the twisted, perforated strip of metal *e* shown in Figs. 7 and 8. Each wall slab may also be provided with suitable countersunk bores *e'*, the countersunk apertures of which, *e²*, accommodate the heads and nuts of removable bolts *e³*. The bores *e'* may be lined with bushings *e⁴* to reinforce the bores and save them from the wear incidental to repeated assembling and separating of the parts. The wall slabs are built up in tiers 100 on their narrow edges and are separably secured to each side of the uprights by means of the removable bolts *e³* passing through the uprights; and the slabs of the several 105 tiers are preferably arranged in staggered or 110

- broken joint relation as shown in Fig. 2. The end joints between the slabs fall upon the uprights, and the lateral lugs or projections a' on the uprights afford sufficient surface for the fastening bolts without making the uprights too broad. When the wall surface is no longer than a single slab, as is the case at either side of the door F (Fig. 1) this staggered arrangement is not used.
- 10 The inner and outer walls thus formed are spaced apart by the uprights and an air space α is provided. The inner wall covering may be omitted if the use to which the building is to be put does not require a double wall and air space.
- 15

In order to protect the bore e' and bolt e^3 from the weather, to prevent the rusting of the bolt and leakage through the bore, and to conceal the fastening means and provide 20 a decorative finish, caps G of porcelain, metal, or any suitable material, are provided to cover the ends of the bolts and the bores, and are fastened to the surface of the walls by cement or plaster g , which fills the space 25 within the aperture e^2 and underneath the cap, thus forming an effective seal.

The roof consists of a plurality of slabs H, each provided at its upper edge adjacent to the ridge pole with a flange h , which fits 30 underneath the bead d and provides a seat for the removable bolts h' passing through the opposed flanges h and the intervening ridge pole D. Each roof slab is also provided with the upturned flange h^2 along one 35 of its lateral edges, and a similar flange having the covering strip h^3 ; along its other edge, so that each slab constitutes a trough, well adapted to shed water, and when a number of such slabs are placed close together 40 edge to edge with the strip h^3 extending over the edge of the adjacent flange h^2 , a roof is provided consisting of a plurality of troughs adapted to drain away water and having no upwardly exposed 45 joints. Each slab H preferably extends from the ridge pole to the eaves and forms a continuous trough from ridge pole to eaves. The lateral flanges not only provide the sides of the trough but serve as strengthening ribs or trusses. Removable bolts h^4 50 passing through the flanges h^2 of the slabs, fasten the slabs together edge to edge. Removable bolts H^5 passing through lugs b on the side sills B, and into sockets on the under

side of the roof slabs, secure the roof slabs 55 at their lower ends.

Referring now to Fig. 5, I have shown a modified form of fastening means between the wall slabs and uprights, by means of which a wall slab may be held in place by a 60 blind fastening. The upright A' is provided with the offset projections or flanges a^2 , through which a screw s passes and is held by a reinforced bore e^5 extending into but only part way through slab E, thus not 65 exposing the fastening means at all on the outer face of the slab. The opposite slab may also be attached by a similar blind fastening means or may be attached by a bolt s' passing through the slab as already 70 described.

Still another form of blind fastening means is shown in Fig. 6, consisting of wire loops l , the ends of which are embedded and anchored in the concrete slab, projecting 75 from recesses m in the opposed faces of the slabs. These loops are connected by a wire link n which is twisted, as shown, drawing the slabs E, E, toward each other and in tight engagement with the uprights A. 80

All of the parts, namely, the upright beams, cross beams or sills, wall slabs and roof slabs, are composed of concrete or the like, and the frame members are reinforced as described by longitudinal metal rods embedded therein. Thus a fireproof building 85 is provided composed of what may be termed "concrete lumber" throughout, fastened together with metallic fastening means. 90

I claim:

A knockdown or portable building comprising a frame made up of a plurality of upright and cross members, a plurality of wall slabs of concrete or the like, said wall 95 slabs provided with countersunk bores adapted to receive removable bolts for separately fastening said slabs to said frame, caps covering said countersunk bores, and cement or the like filling the countersunk 100 apertures of said bores and securing said caps in place.

Signed by me at Boston, Massachusetts, this ninth day of April 1909.

DAVID CRAIG.
